UNITED STATES PATENT OFFICE.

EDGAR D. DICKINSON, OF SCHENECTADY, NEW YORK, ASSIGNEE TO GENERAL ELECTRIC COMPANY, A CORPORATION OF NEW YORK.

EXTRACTING STEAM FROM TURBINES FOR INDUSTRIAL PURPOSES.

1,085,114.

Specification of Letters Patent.

Patented Jan. 27, 1914.

Application filed August 7, 1912. Serial No. 713,707.

To all whom it may concern:

Be it known that I, EDGAR D. DICKINSON, a subject of the King of Great Britain, residing at Schenectady, county of Schenectady, State of New York, have invented certain new and useful Improvements in Extracting Steam from Turbines for Industrial Purposes, of which the following is a specification.

10 This invention relates to steam turbines from which a certain amount of steam is led off from an intermediate stage for heating or other industrial purposes. In order to maintain the pressure in the stage from 15 which the steam is extracted, some form of valve, or a number of separate valves, must be provided to close off nozzles leading to the next lower stage. But when a turbine is thus arranged, certain precautions must 20 be taken to prevent the occurrence of dangerous conditions during operation. The three principal things to be guarded against are, first, the running away of the turbine by a back flow of low-pressure steam from 25 the heating pipe, should the load be removed; second, the occurrence of excessive pressure differences on opposite sides of the diaphragm carrying the stage-valves above mentioned; and, third, variation of the pressure in the heating line beyond proper limits, owing to the quantity of steam available.

The present invention aims to provide 30 mechanism which will automatically care for these possibilities of trouble by means of a valve inserted in the heater pipe and serving both as a pressure regulator and as a shut off valve, as the occasion may arise.

40 The invention will be better understood from the following detailed description, taken in connection with the accompanying drawings, in which—

Figure 1 is a side elevation of a portion of a steam turbine equipped with my invention, the figure being partly in section; Fig. 45 2 is a somewhat similar view of a modification of the invention; Fig. 3 is an elevation at right angles to Fig. 2; and Fig. 4 is a section of the valve shown in Fig. 2.

50 The turbine shown in Fig. 1 has five stages with two bucket-wheels 1 per stage. Diaphragms 2 separate the stages, and the nozzles 3 in the diaphragm 2 between the second and third stages are controlled by 55 hand-valves 4, so that one or more of said

nozzles can be closed to maintain the proper pressure in subsequent stages. A heater pipe 5 leads off from the casing 6 of the turbine between the second and third stages. The flow of low-pressure steam through 60 said pipe is controlled by a combined throttle and shut-off valve 7, preferably of the balanced type. The stem of said valve carries a dashpot 8 to dampen the movement of the valve when it closes automatically. Said stem also has a lug 9 which is normally engaged by a spring catch 10 pivoted on a block 11 carried by the rod 12 of a hydraulic or other motor 13. The pilot valve of this motor is arranged in a chest 70 14 and its stem 15 is pivoted to a floating lever 16, one end of which fulcrums on the rod 12 of the motor, while its other end is connected by the link 17 to a lever 18 arranged to be actuated by a diaphragm or 75 other movable abutment inclosed in a casting 19 and exposed on one side to the pressure of the steam in the heater pipe after it passes the valve 7. This pressure acting upon said abutment causes the motor 13 to 80 regulate the position of the valve in such a manner as to maintain an approximately uniform pressure in the heating system. In order to enable this valve to operate as a shut-off in case of no load, there is arranged adjacent to the tail of the spring catch 10 a bar 20 parallel with the path of movement of said catch as the rod 12 moves up and down. This bar is supported on links 21 so that it moves like a parallel ruler 90 and can trip the catch at any point in its travel. The bar is connected by a rod 22 with an emergency governor 23 on the turbine shaft, so that if the turbine attempts to run away by reason of a backward flow of 95 low-pressure steam from the heating system, the catch 10 will be promptly tripped and the valve 7 will be closed by its own weight assisted by a spring 24 shown in dotted lines.

100 In the modification shown in Figs. 2, 3 and 4, the motor 13 is dispensed with, and the stem of the valve 7 is operated directly by the diaphragm 25 in the casing 26 which is open to the heating pipe. The stem 27 of the valve 7 is tubular and is sleeved upon the rod 28 which connects the diaphragm with the counterbalanced lever 29. A spring 30 thrusts down the valve stem when the spring catch 10 is tripped; said spring being 110

housed in an inverted cup 31 secured to the rod 28 and carrying the spring catch 10.

An opening 32 in the heating pipe is controlled by a weighted valve 33, so adjusted 5 as to prevent the difference in pressure on opposite sides of the diaphragm 2 carrying the hand operated valves 4 from exceeding a predetermined fixed amount, the steam escaping through the by-pass pipe 34 to the 10 stage below the hand valves.

In accordance with the provisions of the patent statutes, I have described the principle of operation of my invention, together with the apparatus which I now consider to 15 represent the best embodiment thereof; but I desire to have it understood that the apparatus shown is only illustrative, and that the invention can be carried out by other means.

20 What I claim as new and desire to secure by Letters Patent of the United States, is:

1. The combination with a steam turbine, of a pipe for conveying away steam for heating or other industrial purposes, a valve controlling said pipe, means for automatically regulating said valve to maintain a uniform pressure in the heating system, and means for automatically closing said valve in case the machine exceeds its normal speed.

20 2. The combination with a steam turbine, of a pipe for carrying away steam for heating or other industrial purposes, a valve controlling said pipe, a rod for actuating said valve, a spring catch connecting said 35 rod and valve, a movable abutment exposed to the pressure of the steam after it passes said valve, means whereby said abutment regulates the position of said valve, and means for tripping said catch in case the 40 machine exceeds its normal speed.

3. The combination with a steam turbine, of a pipe for conveying away steam for heating or other industrial purposes, a valve controlling said pipe, a rod for actuating 45 said valve, a spring catch connecting said

valve and rod, means for regulating said valve to maintain a uniform pressure in the heating system, a bar adjacent to said catch having a parallel ruler motion, an emergency governor and means whereby said emergency 50 governor can actuate said bar to trip said catch and permit said valve to close.

4. The combination with a steam turbine, of a pipe for carrying away steam therefrom for heating or other industrial purposes, a valve controlling said pipe, means for automatically operating said valve to regulate the pressure on the steam in the heating system, and means for automatically shutting off said pipe from the turbine in case the 60 turbine exceeds its normal speed.

5. The combination with a multistage turbine, of a pipe for carrying away steam from one of its stages for industrial purposes, an automatic pressure regulating valve for said 65 pipe, a bypass from said stage to the next and means for opening said bypass at a predetermined steam pressure.

6. The combination with a multistage turbine, of a pipe for conveying away steam from one of its stages for industrial purposes, an automatic pressure regulating valve for said pipe, a bypass from said stage to the next, and a weighted valve for opening said bypass at a predetermined steam 75 pressure.

7. The combination with a multistage turbine, of a pipe for conveying away steam from one of its stages for industrial purposes, hand valves controlling the flow of steam from said stage to the nozzles of the next stage, a bypass between said two stages, and a weighted valve for opening said bypass at a predetermined steam pressure.

In witness whereof, I have hereunto set my hand this 5th day of August, 1912.

EDGAR D. DICKINSON.
